ROTARY FLUID PUMP

Samuel Bilsky, Flint, Mich.

Application August 28, 1950, Serial No. 181,899

6 Claims. (Cl. 103—89)

1

The present invention relates to fluid chambers with rotatable sections, and aims to provide a novel and improved mechanism of this character wherein an annular chamber, composed of recessed ring sections with connecting bearing surfaces therebetween and with a fluid inlet in one section and a fluid outlet in another, is adapted for attachment to machinery in a manner to cause one section to be rotated while another remains stationary, rotates at a different rate of speed, or rotates in an opposite direction.

Another object of the invention is to provide a fluid chamber of annular formation for use with machinery requiring the extending of a part of the machinery therethrough and the conveying of fluid to moving parts of the machinery.

Another object of the invention is to provide a fluid chamber in accordance with the preceding objects, wherein a stationary section has a fluid supply opening therein, while a rotary section has a plurality of fluid outlet openings and a series of angularly arranged vanes fixed therein for forcing the fluid in the chamber through said outlet openings.

A further object of the invention is the provision of an annular chamber composed of a pair of annularly recessed ring sections, each consisting of concentric inner and outer cylindrical walls and a flat side wall, said cylindrical inner and outer walls of one section being rotatably connected to the cylindrical inner and outer walls, respectively, of the other section, while the two flat side walls of both sections constitute end walls for the annular chamber.

A still further object of the invention is to provide a fluid chamber as outlined in the preceding object, wherein there is a fluid inlet opening at the outer cylindrical wall of one section and a plurality of fluid outlet openings through the flat side wall of the other section, said fluid outlet openings being provided in bolts that extend through radially arranged openings in the side wall for attaching the section to the part or parts into which the fluid passes.

It is also an object of the invention to provide a fluid chamber of the above-indicated character, which is simple and substantial in construction, economical to manufacture, and thoroughly efficient and practical in use.

These, together with various auxiliary features and objects of the invention which will later become apparent as the following description proceeds, are attained by the present invention, preferred embodiments of which have been illustrated, by way of examples only, in the accompanying drawings, wherein:

2

Figure 1 is a side elevation of the improved fluid chamber with parts broken away and shown in section;

Figure 2 is an elevation and sectional view at right angles to that shown in Figure 1;

Figure 3 is a section taken substantially on line 3—3 of Figure 1;

Figure 4 is a vertical cross section through a slightly modified form of the invention showing the chamber used to lubricate a flywheel bearing on a rotating shaft; and

Figure 5 is a fragmentary sectional view of parts shown in Figure 4, but showing an additional modification.

Referring now more specifically to the accompanying drawings, wherein like numerals designate similar parts throughout the various views, attention is directed first to Figures 1, 2, and 3, wherein it will be seen that there is indicated by the numeral 10 an annular chamber which is composed of a normally stationary section 11 and a normally rotatable section 12. While the sections 11 and 12 will be referred to throughout the description as stationary and rotatable, respectively, for clarification, it is to be understood that rotary movement at different rates of speed or in opposite directions may be imparted to both of said sections.

The sections 11 and 12 are connected together side by side and are both of ring-shaped formation with annular recesses extending inwardly from adjacent sides thereof and opening into one another to provide a closed annular fluid-containing compartment which produces sections, each with an inner and an outer cylindrical wall and a flat side wall. The inner and outer cylindrical walls and flat side wall of the stationary section 11 are designated by the numerals 13, 14, and 15, respectively, while similar walls of the rotatable section 12 are indicated by the numerals 16, 17, and 18.

At the locations where the cylindrical walls 13 and 14 of the section 11 are connected to the cylindrical walls 16 and 17, respectively, of the section 12, the inner cylindrical walls 13 and 16 are provided with abutting inwardly directed annular flanges 19 and 20, while the outer cylindrical walls 14 and 17 have outwardly directed abutting annular flanges 21 and 22. The flanges 20 and 22 on the section 12 are of greater widths and thicknesses than the flanges 19 and 21 of the section 11, are recessed annularly to receive the flanges 19 and 21, and have attached thereto by bolts 23 and 24, rings 25 and 26 that engage over the flanges 19 and 21 for retaining same in the recesses of the flanges 20 and 22 and for

rotatably connecting the sections together. For supporting the two sections 11 and 12 in true concentric relationship during rotary movement, bearing surfaces 27 and 28 are provided by extensions 29 and 30 on the walls 16 and 17 of the section 12 projecting into annular cutouts in the walls 13 and 14 of the section 11.

In the outer cylindrical wall 14 of the stationary section 11 is an opening 31 into which is threaded a pipe connection 32 for a fluid supply line. While only one inlet opening is shown, it is to be understood that there may be any number of same. Also on the stationary section 11, and attached to the flat wall 15 thereof by bolts 33, is a bracket 34 with outwardly and forwardly directed perforated arms 35 adapted for attachment to a stationary part of the machinery.

To provide fluid outlet openings and a means of attaching the rotatable section 12 to a rotating part of the machine to which fluid is to be supplied, a plurality of tubular bolts 36 are extended through spaced holes 37 in the flat side wall 18 of the section 12 for engagement with said wall upon threading of said tubular bolts into the rotatable part of the machinery. The heads and threads of the tubular bolts attach the parts together, while the openings 38 through the bolts communicate the interior of the chamber with any desired source of fluid conveyance on the machinery.

Within the fluid compartment and arranged at slight angles are perforated vanes 39 fixed to both cylindrical walls 16 and 11 and side wall 18 of the rotatable section 12 and projecting into the section 11. The vanes 39 are spaced apart and are staggered with respect to the fluid outlet openings for agitating the fluid in the chamber while forcing the same through the openings. The perforations in the vanes increase agitation of the fluid and provide for efficient cooling of the fluid when contacting or exposing exterior wall surfaces of the chamber to colder elements than that of the temperature of the fluid in the chamber.

Reference is now made to Figure 4, which illustrates a slight modification of the invention, and shows the fluid chamber attached to and arranged for lubricating a flywheel bearing of a heavy press. Bearings of this type are difficult to lubricate with a piped lubrication system because the flywheel rotates on a rotatable shaft. For this reason, the bearings are almost always oiled or greased by hand; this requires that operation of the press be ceased so that the oiler may safely climb up onto the top of the press to reach the flywheel oil or grease cups to supply the necessary lubricant. Illustrated is a portion of a press of this type showing a main frame 40 on which a bearing 41 is arranged for rotatably supporting the drive end of a crank shaft 42. Externally of the bearing 41 and rotatably mounted, as at 43, on the protruding drive end of the crank shaft 42 is a power-driven flywheel 44 which is rotated constantly during operation of the press, and which rotates the crank shaft 42 to raise and lower the ram, not shown, upon engagement of the clutch 45. An unusual problem of lubrication is presented because the crank shaft 42 sometimes rotates with the flywheel 44 and at other times, the flywheel is rotated independent of and on the crank shaft, and it is for lubricating this type of bearing that the present invention is especially adapted.

The only difference in this form of the invention

over that previously described is that the inwardly directed flanges 19 and 20 on the stationary section 11 and rotatable section 12, respectively, ring 25, and perforated vanes 39 have been omitted. In lubricating parts of this kind where there is either pressure or gravity feed from the fluid chamber to a bearing or the like, vanes 39 are not used, and seals at the connections of the inner cylindrical walls 13 and 16 are not required.

As can be seen, the stationary section 11 is secured to the frame 40 of the press by bolting the legs 35 of the bracket 37 to said frame, while the rotatable section 12 is secured to a side of the flywheel 44 by the tubular bolts 36 which communicate with passageways 46 leading to the bearing surfaces 43.

Sometimes, flywheels or any other element to which the rotatable sections 12 are to be attached have not had the attaching surface thereof finished off smoothly, or for some other reason they require that the rotatable section 12 be spaced therefrom, threaded bushings 47, such as illustrated in Figure 5, may be used to provide aligned local engagement at the attaching points. Also in Figure 5, spacing collars 48 are shown placed between the brackets 34 and the stationary section 11 where the distance between parts to which the sections of the chamber are to be attached requires the use thereof.

In operation, the rotatable section 12, being securely attached to a rotatable member of the machine, is rotated therewith and relative to the stationary section 11; and fluid entering the stationary section 11 by pipe line or by any other suitable manner of conveyance either flows by gravity or is forced, either by pressure from the pipe line or by movement of the vanes, through the tubular bolts 36 and into the movable part of the machinery to which the section 12 is attached. The bearing surfaces and fluid sealing structures between moving parts of the rotatable section 12 and the stationary section 11 prevent leakage at the rotatable connections of the sections, except in the case illustrated in Figure 4 where the container is used for gravity feed lubricating purposes and where a slight leakage of lubricant at the connection of the inner cylindrical walls 13 and 16 is not objectionable.

In view of the foregoing description taken in conjunction with the accompanying drawings, it is believed that a clear understanding of the construction, operation, and advantages of the device will be quite apparent to those skilled in this art. A more detailed description is accordingly deemed unnecessary.

It is to be understood, however, that even though there is herein shown and described preferred embodiments of the invention, various changes may be made without departing from the spirit and full intentment of the invention.

What is claimed is:

1. A fluid chamber forming member composed of a stationary ring section and a rotatable ring section arranged end to end in axial engagement with one another and with annular recesses in both sections concentric to and opening into one another; each of said sections comprising an inner cylindrical wall, an outer cylindrical wall, and a flat side wall; said stationary section having a fluid inlet opening to the annular recess therein; said rotatable section having a series of fluid outlets through the flat side wall thereof; and members connecting said sections together

for movement of the rotatable section with respect to the stationary section.

2. A fluid chamber forming member composed of a stationary ring section and a rotatable ring section arranged end to end in axial engagement with one another and with annular recesses in both sections concentric to and opening into one another; each of said sections comprising an inner cylindrical wall; an outer cylindrical wall, and a flat side wall; said stationary section having a fluid inlet opening to the annular recess therein; said rotatable section having a series of openings through its flat side wall; attaching bolts in the openings in the flat side wall of the rotatable section; said bolts having fluid outlet openings therethrough communicating with the annular recess of said rotatable section; and members connecting said sections together for movement of the rotatable section with respect to the stationary section.

3. A fluid chamber forming member composed of a stationary ring section and a rotatable ring section arranged axially end to end and with annular recesses in both sections concentric to and opening into one another; each of said sections comprising an inner cylindrical wall, an outer cylindrical wall, and a flat side wall; said stationary section having a fluid inlet opening to the annular recess; said rotatable section having a series of fluid outlets through the flat side wall thereof; said inner and outer cylindrical walls of both sections having bearing surfaces thereon in engagement with one another; and members connecting said sections together for movement of the rotatable section with respect to the stationary section.

4. A fluid chamber forming member composed of a stationary ring section and a rotatable ring section arranged axially end to end and with annular recesses in both sections concentric to and opening into one another; each of said sections comprising an inner cylindrical wall, an outer cylindrical wall, and a flat side wall; said stationary section having a fluid inlet opening to the annular recess; said rotatable section having a series of fluid outlets through the flat side wall thereof; a plurality of vanes in the annular recesses of both sections and fixed to the inner and outer cylindrical walls and flat side wall of the rotatable section and each extending in a plane angularly disposed with respect to the plane of

said flat side wall to which it is fixed; and members connecting said sections together for movement of the rotatable section with respect to the stationary section.

5. A fluid chamber forming member composed of a stationary ring section and a rotatable ring section arranged axially end to end and with annular recesses in both sections concentric to and opening into one another; each of said sections comprising an inner cylindrical wall, an outer cylindrical wall, and a flat side wall; said stationary section having a fluid inlet opening to the annular recess; said rotatable section having a series of fluid outlets through the flat side wall thereof; a plurality of perforated vanes in the annular recesses of both sections and fixed to the inner and outer cylindrical walls and flat side wall of the rotatable section and each extending in a plane angularly disposed with respect to the plane of said flat side wall to which it is fixed; and members connecting said sections together for movement of the rotatable section with respect to the stationary section.

6. A fluid chamber forming member comprising a pair of ring sections arranged end to end in axial engagement and concentric to one another, one of said ring sections having an annular recess therein and a fluid inlet opening to said recess, a plurality of spaced vanes fixed to the other of said ring sections and extending into the annular recess of the first-mentioned ring section, said vanes extending in planes each angularly disposed with respect to the radial plane of the ring section to which it is affixed, said section with said vanes having fluid outlet openings therein, both of said ring sections having bearing surfaces thereon engaging one another at adjacent sides of said sections, and members connecting the sections together in a manner to permit rotation of one section with respect to the other.

SAMUEL BILSKY.
